HOISTING SLING

Filed Aug. 1, 1930

UNITED STATES PATENT OFFICE

ALARIK LUNDQUIST, OF PORTLAND, OREGON

HOISTING SLING

Application filed August 1, 1930. Serial No. 472,304.

The invention relates to improvements in hoisting slings especially adapted and arranged for use in conjunction with hoisting apparatus, the primary object of the invention being to provide a simple and efficient device of this character, capable of economical construction and highly efficient in use.

Another object of the invention is the provision of a hoisting sling of the character indicated, so constructed and arranged as to prevent injury or damage to the packages hoisted.

Another object of the invention is the provision of a hoisting sling of the character indicated, having improved means of attachment or connection with a hoisting element.

Other objects will appear hereinafter.

The invention consists of the combinations and arrangements of parts hereinafter described and claimed.

The invention will be best understood by reference to the accompanying drawings forming a part of this specification, and in which

Fig. 1 is a perspective view of a hoisting sling embodying the invention, and shown in position of use, and

Fig. 2, a similar view of a modified form of construction.

The form of construction illustrated in Fig. 1 of the drawings comprises a relatively wide flexible belt 3, preferably of cotton, leather, or the like, and adapted and arranged to embrace or encircle the objects or articles to be hoisted. The belt 3 is provided at one end with a back-turned loop, or flap, 4, secured thereto as indicated by suitable rivets, and forming a securing loop 5. A transverse rod is mounted as shown in the loop 5, said rod being provided at opposite ends with eyes 6, swiveled to the ends 7 of the flexible loop 7, preferably in the form of a wire rope, or cable, has its ends secured to the eyes 6, and is adapted and arranged to detachably engage the hook at the end of a hoisting cable 9 or the like.

The strap 3 is provided at its other end also with a back-turned flap 10, forming a securing loop 11, in which is mounted the transverse rod 12 having protruding ends bent to

form hooks 13, adapted and arranged to slidably engage the sides of the loop 7, as shown. By this arrangement, a slip-noose is formed which may be readily placed around articles or objects, such as sacks of sugar, grain, and the like, for hoisting purposes, and which will not tear or cut said sacks, or other objects engaged. The sling disclosed will be found to be especially adapted for use in loading and unloading ships; is of great strength; is waterproof and non-kinkable; and may be readily applied to or removed from the object hoisted. The wire cables, or ropes, in the sling, may be readily replaced when necessary, and the sling will thus last a long time.

A second flexible loop 14, preferably of rope, is also passed through the securing loop 11, and twisted together at 15 and forming an eye 16. Another loop 17 also preferably of rope, is passed through the securing loop 5, as shown. As the sling is emptied, the loop 14-16 is looped through the loop 17, and the sling is returned to loading position by engaging the loop 17 with the hook 8. The loops 14-16 and 17 may also be employed to advantage in manipulating the sling when placing it around or removing it from the object to be hoisted. This form of the device is especially adapted for use in loading into railroad cars or narrow quarters where the belt is liable to be rubbing against doors, and the like, and thus wearing out.

In the form of construction illustrated in Fig. 2, the belt 3 is provided at each end with triangular metal loops 18 and 19 secured to securing loops 11 and 5, as indicated. The loop 18 passes through a tube or pipe 18' which prevents rubbing against loop 11 and furnishes additional reinforcement. The loop 19 is adapted and arranged to engage a double hook 20 loosely pivoted at the apex of the triangular metallic loop 21, adapted and arranged to slide upon the body of the belt 30, as shown, the base of the loop 21 being provided with a roller 22 to facilitate such sliding. This arrangement forms a simple and efficient slip-noose construction which may be readily applied to or removed from the objects to be hoisted. This form of con-

struction is especially adapted for use in situations where there is no especial danger of rubbing, and is especially adapted for use in loading such things as lumber, paper, etc., 5 where there is little or no swaying or swinging against sides of the hatchways of the ship, or the like. The loose hook 20 will not tear or mar the enclosed objects or other parts of the sling.

10 While I have illustrated and described the preferred forms of construction for carrying my invention into effect, these are capable of variation and modification without departing from the spirit of the invention. I therefore do not wish to be limited to the precise details disclosed, but desire to avail myself of such variations and modifications as fall within the scope of the appended claims.

15 Having thus fully described my invention, what I claim as new and desire to secure by Letters Patent is:

20 1. A hoisting sling comprising a flexible belt; metal loops secured to the ends of said belt; and a loop slideable on the body of said belt, and having a hook detachably engaging the loop on one end of said belt.

25 2. A hoisting sling comprising a flexible belt having its ends turned backwardly upon itself to form securing loops; triangular metal loops secured in said securing loops a triangular metal loop slideable on said belt, a hook being formed at the apex thereof to detachably engage one of the loops on an end of said belt; and a roller mounted on the base of said slideable triangular loop, said roller sliding against said belt.

30 In witness whereof, I have hereunto set my hand this 21st day of July, 1930.

ALARIK LUNDQUIST.
